UNITED STATES PATENT OFFICE.

WILLIAM DUBILIER, OF NEW YORK, N. Y.

WIRELESS APPARATUS AND METHOD THEREFOR.

1,279,850.

Specification of Letters Patent. Patented Sept. 24, 1918.

Application filed May 6, 1913. Serial No. 765,835.

To all whom it may concern:

Be it known that I, WILLIAM DUBILIER, a citizen of the United States, residing at New York, in the county of New York, 5 State of New York, have invented a new and useful Wireless Apparatus and Method Therefor, of which the following is a specification.

The object of my invention is to provide 10 a sending apparatus which will produce efficiently electrical oscillations suitable for use in wireless telegraphy, and a method of producing such oscillations.

Further specific objects and advantages 15 of my invention will be in part obvious and in part specifically mentioned hereinafter.

For purposes of illustration I have shown 20 several forms of my invention, which forms are to be considered merely as typical examples of the principle thereof.

In the drawings,

Figure 1 shows an electromagnetic vibrator adapted to be used in producing oscillations;

25 Fig. 2 shows a system for carrying out this invention, in which the vibrator shown in Fig. 1 is adapted to be used.

Fig. 3 shows, diagrammatically, another arrangement for carrying out this invention; and

Fig. 4 shows, diagrammatically, a still further arrangement when used for wireless telegraphy, with an aerial and ground.

Figs. 1 to 4 illustrate the application of 35 a vibrator or oscillator to a wireless sending device. In Fig. 1 I have shown a simple form of electromagnetic vibrator consisting of a coil a wound upon a core a^0 , a spring finger o being mounted adjacent the end of 40 the core, and carrying a movable contact d^1 . A fixed contact d^2 is opposed to contact d^1 , and a spring holds the movable contact d^1 against fixed contact d^2 , except when an armature i attached to spring finger o , is 45 attracted by the core a^0 .

As shown in Fig. 2, such an interrupter d may be used in a primary circuit containing any suitable alternating or direct current source of energy, an inductance a and the primary of a transformer c . An oscillating circuit is provided by means of a condenser e which is in parallel with the interrupter and transformer primary c .

50 In the operation of the apparatus shown in Fig. 2 current passing from the source of energy, through inductance a , interrupter

d , transformer primary c , breaks the primary circuit at contacts d^1 and d^2 . The condenser e is in parallel with the gap at d^1-d^2 , and is charged by the action of the arc 60 across said gap. Inductance a prevents surges from traveling back through the generator circuit, and also assists in charging the condenser due to the self inductive effect obtained when circuit is broken at d^1-d^2 . 65 The oscillations are then extinguished by the gap at d^1 and d^2 . The apparatus operates most efficiently when the period of vibration of spring o , of the vibrator, is in a selected ratio to the natural frequency of the oscillating circuit $e-d-c$, that is to say, when such period of vibration is either equal to, or a harmonic of, the natural frequency of the oscillating circuit.

Figs. 3 and 4 illustrate modifications of 75 the circuit arrangement used in Fig. 2, a capacity f , and an inductance g being placed in parallel with interrupter d in Fig. 3, and a condenser p being placed across the primary c in Fig. 4.

An apparatus of the type shown in Figs. 1 to 4 is very light in weight, owing to the fact that a simple electromagnetic vibrator is used to produce oscillations, and the cost of manufacture is correspondingly lessened. 85 As a closed circuit condition obtains in starting the oscillations, a high primary potential is not necessary, but a direct current source of energy of low voltage is sufficient to operate the apparatus efficiently, the high potential of the oscillating circuit being effected through gap d^1-d^2 and inductance a . Because of the features of low cost, lightness in weight, simplicity and possibility of operation with low voltage, the apparatus 90 is specially suited for portable sets, and for use in connection with moving bodies, such as aeroplanes, boats, etc.

What I claim and desire to secure by Letters Patent is:—

1. A wireless apparatus comprising a primary circuit consisting of an inductance, the primary of a transformer, and an electromagnetic vibrator having its movable contact biased to close such circuit, and an oscillating circuit comprising a condenser, said vibrator and said transformer primary, whereby, on the opening of the primary circuit, oscillations from said condenser are produced in said oscillating circuit and extinguished by the vibrator gap.

2. A wireless apparatus comprising a

primary circuit consisting of an inductance, the primary of a transformer, and an electromagnetic vibrator having a low frequency period of vibration and having its 5 movable contact biased to close such circuit, and an oscillating circuit comprising a condenser, said vibrator and said transformer primary, whereby, on the opening of the primary circuit, oscillations from said 10 condenser are produced in said oscillating circuit and extinguished by the vibrator gap.

3. A wireless apparatus comprising a primary circuit consisting of an inductance, the 15 primary of a transformer, and an electromagnetic vibrator having a low frequency period of vibration and having its movable contact biased to close such circuit, and an oscillating circuit comprising a condenser, said vibrator and said transformer primary, whereby, upon the opening of the primary circuit, oscillations of radio frequency are produced from said condenser across the vibrator contact and extinguished 20 by the vibrator gap, the period of vibration of said vibrator being in a selected ratio with respect to the frequency of the oscillating circuit.

4. A wireless apparatus having a primary 30 circuit, comprising an inductance, an electromagnetic vibrator having a low frequency period of vibration and the primary of a transformer, and an oscillating circuit of radio frequency comprising a condenser, 35 said vibrator and said primary.

5. A wireless apparatus having a primary circuit consisting of an inductance, an electromagnetic vibrator and the primary of a transformer, and an oscillating circuit comprising 40 a condenser, said vibrator and said primary.

6. A wireless apparatus having a primary circuit consisting of an inductance, an electromagnetic vibrator and the primary of a 45 transformer, and an oscillating circuit of radio frequency comprising a condenser, said vibrator and said primary, the period of vibration of the vibrator being in a selected ratio with respect to the frequency of 50 the oscillating circuit.

7. A wireless apparatus having a primary circuit containing a condenser charging device comprising an electromagnetically actuated oscillator, and an oscillatory circuit of 55 radio frequency including a condenser and said oscillator, the period of vibration of the oscillator being in a selected ratio with

respect to the frequency of the oscillating circuit.

8. A wireless apparatus having a primary 60 circuit containing a condenser charging device comprising an electromagnetically actuated oscillator, and an oscillatory circuit of radio frequency including a condenser and said oscillator.

9. A wireless apparatus having a primary 65 circuit containing a condenser charging device comprising an oscillator, and an oscillatory circuit of radio frequency including a condenser and said oscillator.

10. In an apparatus for producing electric 70 oscillations an oscillating circuit, a vibrating electrode, and a fixed electrode in said circuit, and means whereby the period of vibration thereof may be of the same frequency as the natural frequency of the 75 oscillating circuit.

11. In apparatus for the production of 80 electric oscillations the combination of an oscillator, of means associated therewith for producing oscillations having the characteristic of an undamped nature for a certain period, and a damped or quenched nature for a further period, said means including an oscillatory circuit the inductance 85 of which has a condenser shunted across it.

12. In an apparatus, the combination of a 90 current supply, an oscillator, an oscillating circuit containing an inductance and capacity, said inductance having a condenser shunted across it, the natural frequency of the oscillating circuit being in a selected ratio to the working frequency of the oscillator.

13. A wireless apparatus having a primary 95 circuit containing a condenser charging device comprising an oscillator, and an inductance, and an oscillatory circuit including a condenser, said oscillator and the primary of a transformer.

14. A wireless apparatus having a primary circuit containing a condenser charging device comprising the winding and contacts of an electromagnetically actuated vibrator, and an oscillatory circuit comprising a condenser, said oscillator contacts, and the primary of a transformer.

In witness whereof, I have hereunto signed my name in the presence of two subscribing witnesses.

WILLIAM DUBILIER.
